CLAIM

We claim the ornamental design for a minimal waste dispensing tip, as shown and described.

DESCRIPTION

FIG. 1 is a top perspective view of a minimal waste dispensing tip;

FIG. 2 is a front elevation view thereof, where a rear elevation view is identical to the front elevation view;
FIG. 3 is a left side elevation view thereof, where a right side elevation view is identical to the left side elevation view;
FIG. 4 is top-to-bottom section view thereof, taken along line 4-4 of FIG. 3;

FIG. 5 is a top plan view thereof;

FIG. 6 is a bottom plan view thereof; and,

FIG. 7 is a bottom perspective view thereof.

The broken lines illustrate boundaries that form no part of the claimed design.
